UNITED STATES PATENT OFFICE.

WILLIAM H. LEWIS, OF ROANOKE, VIRGINIA, ASSIGNOR OF ONE-HALF TO
JAMES J. McCARTHY, OF CHICAGO, ILLINOIS.

BRAKE.

No. 851,892.

Specification of Letters Patent.

Patented April 30, 1907.

Application filed May 24, 1905. Serial No. 262,040.

To all whom it may concern:

Be it known that I, WILLIAM H. LEWIS, a citizen of the United States, residing at Roanoke, in the county of Roanoke and State of Virginia, have invented certain new and useful Improvements in Brakes, of which the following is a specification, reference being had to the accompanying drawings.

My invention relates to brakes for railway or other cars, and has for its object to provide new and improved means for supporting the brake-shoes and by which the brake-shoes may be applied to the wheels.

To this end my invention consists in an improved construction of brake-beam by which the weight of the beam may be very considerably reduced without loss of strength, as will appear from the following description.

What I regard as new is set forth in the claims.

In the accompanying drawings,--Figure 1 is a rear view of a portion of a truck, illustrating my improvements; Fig. 2 is a plan view thereof; Fig. 3 is an end view, some parts being in section; and Fig. 4 is a section on line 4--4 of Fig. 2.

Referring to the drawings,--5 indicates a part of a truck-frame, and 6--7 the wheels at one end thereof.

8--9 indicate the brake-heads, which may be of any suitable construction. They are suspended from the truck-frame 5 by stirrups 10, as shown in Figs. 1 and 3, and as indicated by dotted lines in Figs. 1, 2 and 3 they are fitted upon the ends of the compression-member hereinafter described,--suitable sockets being provided in them for that purpose. The brake-beam is composed of a Y-iron compression-member 11, a fulcrum-post 12, or strut 12, and two rods 13--14, the ends of which are connected to the brake-heads 8--9, one at each side of the horizontal flange of the compression-member, as shown in Figs. 1 and 3, so that said flange of the compression-member is included between them. Said rods extend around the inner end of the fulcrum-post 12, the outer end of which is connected centrally with the compression-member 11, as shown in Fig. 2, so that said parts together form a truss, the rods 13--14 being the tension-member thereof. The inner end of the fulcrum-post 12 is provided with seats or grooves 15--16 to receive the rods 13--14, as shown in Figs. 3 and 4, and thereby hold

said rods in place. Said post is provided with a lug 17 at its inner end, to which is secured the lower end of a chain 18, or other suitable connection, by which the inner end of the post is suspended from the truck-frame; and in the construction shown the upper end of the chain 18 is connected by a bolt 19 with a spring-arm 20 secured to the truck-frame, as shown in Fig. 3.

As illustrated in Fig. 4, the compression-member is T-shaped in cross-section, having a horizontal web 21 which is perpendicular to the base 22 of the compression-member. Said web 21 is fitted in a suitable groove in the outer end of the post 12 and is secured therein by rivets 23, or other suitable means.

As shown in Fig. 3, the rods 13--14 are connected with the brake-heads at opposite sides of the web 21, so that tension is applied to the compression-member equally at both sides of said web.

24 indicates a brake-lever, which, as best shown in Figs. 2 and 3, is fulcrumed upon a pin 25 fitted in the post 12. The lever 24 passes through a suitable slot 26 in said post, which is of sufficient length to permit said lever to play freely therein at the proper angle. The lever 24 is connected up for operation in the usual way,--its lower end being connected by a rod 27, or other suitable means, with the brake-mechanism at the opposite end of the truck, or with that of another truck, while its upper end is connected with suitable actuating-mechanism.

By the construction described, I provide a very light but strong brake-beam, which, in practice, I have found to be equal to that of other beams having fifty per cent more material, and it meets every requirement for pressure required for high-speed brakes.

So far as the broader claims are concerned, my invention is not restricted to the specific embodiment thereof illustrated in the drawings, but includes modifications or variations which do not depart from the spirit of the invention.

That which I claim as my invention and desire to secure by Letters Patent is,--

1. A brake-beam, comprising a compression-member T shaped in cross section, brakes carried by said compression-member at the web side thereof, a fulcrum-post connected with the web of said compression-

member, means connecting the inner portion of said fulcrum-post with the end portions of said compression-member, and a lever fulcrumed upon said post.

5 2. A brake-beam, comprising a compression-member T-shaped in cross section, brakes carried by said compression-member at the web side thereof, a fulcrum-post connected with the web of said compression-member, rods connecting the inner portion of said fulcrum-post with the end portions of said compression-member, and a lever fulcrumed upon said post.

15 3. A brake-beam, comprising a compression-member T-shaped in cross section, brakes carried by said compression-member at the web side thereof, a fulcrum-post connected with the web of said compression-

member, rods connected with the end portions of said compression-member at opposite sides of the web thereof, and a lever fulcrumed upon said post.

4. A brake-beam, comprising a compression-member T-shaped in cross-section, brakes carried by said compression-member at the web side thereof, a fulcrum-post connected with the web of said compression-member, and means connecting the inner portion of said fulcrum-post with the end portions of said compression-member at opposite sides of the web thereof.

WILLIAM H. LEWIS.
